TUBE FEEDING CHAIN MECHANISM FOR AXMINSTER LOOMS

Filed June 30, 1922

Patented Oct. 30, 1923.

UNITED STATES PATENT OFFICE.

EVERETT E. CLARK, OF WORCESTER, MASSACHUSETTS, ASSIGNOR TO CROMPTON & KNOWLES LOOM WORKS, A CORPORATION OF MASSACHUSETTS.

TUBE FEEDING CHAIN MECHANISM FOR AXMINSTER LOOMS.

Application filed June 30, 1922. Serial No. 571,862.

To all whom it may concern:

Be it known that I, EVERETT E. CLARK, a citizen of the United States, residing at Worcester, in the county of Worcester and State 5 of Massachusetts, have invented a new and useful Tube Feeding Chain Mechanism for Axminster Looms, of which the following is a specification.

This invention relates to chain feeding 10 mechanism for looms of the Moquette type in which the numerous tuft yarns for each pick of the fabric are assembled on a separate yarn spool and are presented between the warp threads by a corresponding number of 15 yarn tubes. These yarn tubes are fixed to a tube frame which also supports the yarn spool and a number of these tube frames and spools are assembled to form a pattern chain of greater or less length and often of very 20 considerable weight.

My invention relates to improvements in the mechanism for intermittently advancing such a pattern chain and particularly to 25 means for manually controlling and reversing the feed thereof.

My invention further relates to arrangements and combinations of parts which will be hereinafter described and more particularly pointed out in the appended claims.

30 A preferred form of the invention is shown in the drawings, in which—

Fig. 1 is a front elevation of parts of a loom frame having my invention applied thereto;

35 Fig. 2 is a side elevation of the parts shown in Fig. 1;

Fig. 3 is an enlarged sectional side elevation taken along the line 3—3 in Fig. 1; and

40 Fig. 4 is a detail side elevation looking in the direction of the arrow 4 in Fig. 1.

Referring to the drawings, I have indicated parts of a loom frame 10 and an upper cross girt 11. A driving shaft 12 for the tube chain (not shown) is supported in bearings on the frame 10 and is intermittently advanced in either direction by the pawl and ratchet mechanism shown in detail in Fig. 3.

This mechanism comprises a pair of ratchet wheels fixed to the shaft 12 and having ratchet teeth facing in opposed directions. A pair of feed pawls 13 and 14 are regularly moved angularly about the axis of the shaft 12 by links 15 which connect the feed pawl supports 16 with a bell crank 17

actuated by a cam 18 on the loom cam 55 shaft 19.

A guard plate or shield 20 is mounted on a fixed pivot 21 and engages studs 22 in the pawls 13 and 14. The guard plate 20 is movable upward and downward from the mid-position shown in Fig. 3 and when in its upward position permits the feed pawl 14 to become operative while the pawl 13 is held inoperative. Similarly, when in its lower position the pawl 13 is operative and the pawl 14 is inoperative.

The parts thus far described in themselves form no part of my present invention and for a more complete disclosure thereof reference is made to the copending application of E. H. Ryon, Serial No. 560,211, filed May 11, 1922.

The guard plate or shield 20 is connected by a link 24 to a reversing arm 25 fixed on a cross rod or shaft 26. This shaft is supported in bearings on the upper cross girt 11 and is provided with hand levers 27 and 28 secured to the opposite ends thereof. The lever 28 has an upward extension 29 on which a latch 30 is pivoted at 31. This latch 80 co-operates with a notched locking plate 32 fixed to the cross girt 11.

A release lever 33 is pivoted at 34 to the hand lever 28 and has a pin and slot connection at 35 with the latch 30. A spring 36 85 normally holds the latch 30 in engagement with the notches of the lock plate 32. A second release lever 38 is pivoted at 39 on the hand lever 27 and is connected by a link 40 to the latch 30.

With the mechanism thus described the loom operator is able to control the pattern chain feed from either side of the loom. For this purpose if he is at the right side 95 of the loom he grasps the lower ends of the hand lever 27 and the release lever 38, pressing them toward each other. This action is effective through the link 40 to withdraw the latch 30 from the notches in the plate 32, after which the release cross rod 26 may 100 be turned by the hand lever 27 to raise or lower the guard plate or shield 20. At the left hand side of the loom the same results may be obtained by simultaneously actuating the hand lever 28 and the release lever 38.

The mechanism described forms a very 105 convenient and accessible means of reversing

or stopping the feed of the pattern chain at any desired point and from either side of the loom.

Having thus described my invention and the advantages thereof, I do not wish to be limited to the details herein disclosed otherwise than as set forth in the claims but what I claim is:—

1. A tube chain feeding mechanism for an Axminster carpet loom comprising a feed shaft, means to angularly advance said shaft intermittently in either direction, reversing mechanism for said means including a pivotally mounted reversing arm, a latch for said arm, a release lever mounted on said arm, and connections from said lever to said latch, whereby said latch may be released.
2. A tube chain feeding mechanism for an Axminster carpet loom comprising a feed shaft, means to angularly advance said shaft intermittently in either direction, reversing mechanism for said means including a shaft, a reversing arm fixed to said shaft and having an extension beyond said shaft, a latch mounted on said extension, and a release lever for said latch mounted on said arm and movable therewith, said release lever having an additional movement independent of said arm to release said latch.
3. A tube chain feeding mechanism for an Axminster carpet loom comprising a feed shaft, means to angularly advance said shaft intermittently in either direction, reversing mechanism for said means including a shaft, a reversing arm on said shaft, a latch for

said shaft, a notched plate fixed to said loom and co-operating with said latch, a spring to engage said latch with said plate, and a release lever mounted on and movable with said reversing arm and connected to release said latch.

4. A tube chain feeding mechanism for an Axminster carpet loom comprising a feed shaft, means to angularly advance said shaft intermittently in either direction, reversing mechanism for said means including a shaft extending transversely across said loom, a reversing arm at each end of said shaft, a latch for said shaft pivotally mounted on an extension of one of said reversing arms, and a lever on each arm connected to release said latch.

5. A tube chain feeding mechanism for an Axminster carpet loom comprising a feed shaft, means to angularly advance said shaft intermittently in either direction, reversing mechanism for said means including a shaft extending transversely across said loom, a reversing arm at each end of said shaft, a latch for said shaft pivotally mounted on an extension of one of said reversing arms, and a lever on each arm connected to release said latch, the handle portions of each associated reversing arm and release lever being so positioned that they may be simultaneously grasped and easily moved by the hand of the operator.

In testimony whereof I have hereunto affixed my signature.

EVERETT E. CLARK.
